UNITED STATES PATENT OFFICE.

FREDERICK A. LANGSTON AND GEORGE A. HOARD, OF CHICAGO, ILLINOIS.

HINGE.

1,416,039.

Specification of Letters Patent. Patented May 16, 1922.

Application filed January 3, 1922. Serial No. 526,598.

To all whom it may concern:

Be it known that we, FREDERICK A. LANGSTON and GEORGE A. HOARD, citizens of the United States, residing at Chicago, in the 5 county of Cook and State of Illinois, have invented certain new and useful Improvements in Hinges, of which the following is a specification.

This invention relates in general to hinges 10 adapted for use in hanging doors and for other purposes where it may be desirable to mount a swinging member.

One of the primary purposes of our 15 present invention is to provide a hinge which will be capable of adjustment to overcome or compensate any sagging or binding of the door.

With this general purpose in view our 20 invention contemplates the provision of a hinge in which the two leaves, one being fastened to the door jamb and the other to the door itself, are relatively adjustable in a vertical plane, and also one in which one of the leaves itself, and preferably that leaf 25 which is attached to the door, may be adjusted horizontally so as to adjust the door toward or from the jamb upon which the hinge is mounted.

Another purpose of our invention is to 30 provide a hinge of the character indicated which will be simple in construction, easy to mount and easy to adjust in both directions, so that the door may be adjusted to and maintained in its proper position, and one 35 which will be economical to manufacture and durable in use.

Other objects and advantages of our invention will be apparent as the same becomes better understood by reference to the 40 following description when considered in connection with the accompanying drawings upon which preferred embodiments of the invention are illustrated. Referring to the drawings—

Fig. 1 is a side elevation of a hinge embodying my invention shown as applied to a door;

Fig. 2 is the bottom view of the hinge shown in Fig. 1;

Figs. 3, 4 and 5 are sectional views on the lines 3—3, 4—4 and 5—5, respectively, of Fig. 1;

Fig. 6 is a plan view of another form of my invention embodied in a hinge;

Fig. 7 is a front view of the hinge shown in Fig. 6;

Fig. 8 is a sectional view on the line 8—8 of Fig. 7; and

Fig. 9 is a sectional view on the line 9—9 of Fig. 6.

Referring now to the drawings more in detail and particularly Figs. 1 to 5 thereof, reference character 11 indicates a door jamb of any preferred construction upon which by means of our improved hinge a door 12 is 65 mounted. The form of hinge illustrated in Figs. 1 to 5, inclusive, is designed particularly for heavy doors, such as cold storage doors, for instance, and embodies two leaves, one of which is attached to the door jamb 11 70 and the other to the door 12.

The jamb leaf comprises a plate 13 adapted to be secured by screws 14, or otherwise, to the door jamb 11, this plate being provided on its outer face with an undercut guideway 15, as best shown in Fig. 4. Near the lower end of this guideway the plate 13 is provided with an outwardly extending stud or lug 16 tapped for the threaded reception of an adjusting supporting screw 17. 80

The other member 18 of the jamb leaf is formed at its base, as indicated at 19 (Fig. 4), to slidably fit within the guideway 15 and this member is provided at its upper and lower ends with ears 21 and 22, respectively, 85 adapted to accommodate the pintle 23 upon which the other leaf of the hinge is pivotally supported. The lower ear 22 rests upon the adjusting screw 17 and by manipulation of this screw the member 18 and the pintle 23 90 carried thereby may be adjusted in a vertical plane to any desired position.

The other, or door leaf of the hinge, comprises a plate 24 adapted to be secured by screws 25, or other fastening means, to the 95 face of the door 12 and is shaped to provide an undercut guideway 26 extending horizontally thereof. At the outer end of the guideway this plate is provided with a bar or abutment member 27 provided with an aperture to receive an adjusting bolt 28, for a purpose which will be later explained.

A second plate or member 29 is shaped to slidably fit within the guideway 26 and carries a pair of ears 31 and 32, respectively, 105 and an outwardly extending projection 33 in which the bolt 28 is anchored. A pintle 34 extending through the ears 31 and 32 pivotally connects the strap 35 with the plate 29, the opposite end of this strap being connected to the member 18 by the pintle 23 as will be apparent from the drawings. 110

Inner and outer lock nuts 36 are threaded onto the bolt 28 at opposite sides of the bar 27, and by tightening or loosening these nuts the member 29 may be adjusted horizontally with respect to the plate 24 and locked in adjusted position. It will be apparent, therefore, that by manipulation of these lock nuts the door may be adjusted horizontally toward or from the jamb 11 and by manipulation of the set-screw 17 the door may be raised or lowered relatively to the jamb. These adjustments provide, therefore a considerable range of adjustment for the door proper so that it can be properly fitted and positioned and sagging or binding of the door, which may result from continued use may be readily relieved. It is understood, of course, that each door is carried by as many hinges as may be necessary to support its weight, and preferably each of them is adjustable as described, so that the position of the door within its frame may be regulated at any time to a fine degree of nicety.

25 Where heavy doors which are required to fit tightly in the jamb, such as cold storage doors, for instance, are employed, I prefer to provide means for insuring a tight fit of the edge of the door against its jamb, which 30 means comprises a yoke 37 secured by screws 38, or otherwise, to the door adjacent its inner edge, this yoke being adapted to accommodate the strap 35 between which and the door proper a leaf spring 39 is interposed. A set-screw 41 equipped with a lock nut 42 is threaded through the outer member of the yoke into engagement with the strap 35 and a tight fit of the door is secured by adjusting this screw so that the spring 39 acting against the strap and the door will 40 force the door against its frame with just the requisite pressure to insure a tight fit.

The form of our invention illustrated in Figs. 6 to 9, inclusive, is more particularly 45 adapted for lighter doors, such as ordinary house doors, for instance. In this form of the invention the jamb leaf comprises the angle-shaped plate 43 which is adapted to be secured to the door jamb and is equipped 50 with an undercut guideway 44 in which there is slidingly mounted the pintle carrying member 45.

The door leaf comprises a plate 46 adapted to be secured to the face of the door and 55 provided with the undercut guideway 47 in which the plate or strap 48 is adapted to be longitudinally adjustable. A bar 49 at the outer end of the guideway 47 is provided with an aperture adapted to receive the 60 adjusting screw 51 which is threaded into a socket 52 extending longitudinally of the plate 48. A lock nut 53 is adapted to hold the screw 51 in adjusted position. The inner end of the plate 48 is shaped to interfit 65 with the extensions of the member 45 and

it is pivotally secured to this member by a pintle 54. An adjusting screw 55 threaded through an outward extension 56 of the plate member 43 forms the support for the member 45, and by manipulation of this screw the vertical position of this member may be adjusted as desired. It will be apparent, therefore, that in this form of the invention vertical adjustment is provided by the screw 55 and horizontal adjustment by the screw 51, the two adjustments together affording a wide range of adjustability for the door so that it may be fitted and maintained in proper position.

While we have shown and described those embodiments of our invention which at present appear preferable, it should be understood that the details of construction are capable of wide modification without departing from the essence of the invention as defined by the following claims.

We claim:

1. In a hinge, the combination of a plate adapted to be attached to a door jamb and provided with an undercut vertically disposed guideway and an outwardly projecting portion at the lower end of the guideway, a pintle-carrying member slidably disposed in said guideway, an adjusting screw threaded through said projecting portion and engaged with said pintle-carrying member, whereby said member is adjustably supported, a leaf strap pivoted on said member, a plate adapted to be attached to a door and provided with an undercut horizontally disposed guideway and an outwardly projecting portion at one end of said guideway, said strap being slidably engaged in said guideway, and an adjustable connection between said strap and the last mentioned projecting portion, whereby the position of said door relatively to said strap may be adjusted.

2. In a hinge, the combination of a plate adapted to be attached to a door jamb and provided with an undercut vertically disposed guideway, a second plate adapted to be attached to the door and provided with an undercut horizontally disposed guideway, a member slidably mounted in the guideway of said first plate, means for vertically adjusting said member in said guideway, a supporting connection pivotally mounted on said member and slidably connected with said second plate, and means for adjusting said supporting member relatively to said second plate to vary the position of the door with respect to the jamb.

3. In a hinge, the combination of a plate adapted to be attached to a door jamb and provided with an undercut guideway, a member slidably disposed in said guideway, means for adjusting the position of said member in the guideway, a second plate adapted to be attached to a door and pro-

vided with an undercut guideway, a connection pivoted to said first member and slidably connected in the guideway of said second plate, and an adjustable connection between said second plate and said member, whereby said member may be adjusted horizontally relatively to said second plate.

4. In a hinge, the combination of a plate adapted to be attached to a door jamb and provided with an undercut vertically disposed guideway and an outwardly projecting stud beneath said guideway, a member slidably disposed in said guideway, an adjusting screw threaded through said stud and adjustably supporting said member, a second plate adapted to be attached to a door and provided with a horizontally disposed guideway and a bar at the outer end of said guideway, a connecting member slidably connected in said guideway and pivoted upon said first mentioned member, and an adjustable connection between said connecting member and said bar, whereby said member may be adjusted horizontally relatively to said second plate.

FREDERICK A. LANGSTON.
GEORGE A. HOARD.
